Primary Examiner — Mary Shannon Malley*Assistant Examiner* — Michelle Marquart Christeon(74) *Attorney, Agent, or Firm* — Kunzler Bean & Adamson, PC; Michael Bartholomew(57) **CLAIM**

The ornamental design for a mirror, as shown and described.

DESCRIPTION

FIG. 1 is a front, left and bottom perspective view of a mirror, showing my design.

FIG. 2 is a rear, right and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front and left perspective view of the mirror in another state; and,

FIG. 10 is another front and left perspective view of the mirror in another state.

The broken lines depict portions of the mirror that form no part of the claimed design.
